CLAIM

The ornamental design for a tube, as shown and described.

DESCRIPTION

FIG. 1 is a front view of a tube showing my new design; FIG. 2 is a rear view thereof; FIG. 3 is a left side view thereof; FIG. 4 is a right side view thereof; FIG. 5 is a top view thereof; FIG. 6 is a bottom view thereof; FIG. 7 is a perspective view thereof; FIG. 8 is a partially enlarged view showing the circled portion in FIG. 1; FIG. 9 is a partially enlarged view showing the circled portion in FIG. 2; FIG. 10 is a partially enlarged view showing the circled portion in FIG. 3; and, FIG. 11 is a partially enlarged view showing the circled portion in FIG. 4.

The evenly spaced broken lines depict portions of the tube that form no part of the claimed design.

The dot-dash broken line lines denote the boundaries of the detail areas and form no part of the claim.
